UNITED STATES PATENT OFFICE.

KENNETH CLAIRE SMITH, OF BEAVER DAM, WISCONSIN, ASSIGNOR TO MALLEABLE IRON RANGE COMPANY, OF BEAVER DAM, WISCONSIN, A CORPORATION OF WISCONSIN.

IMITATION STOVE.

1,270,888.

Specification of Letters Patent.

Patented July 2, 1918.

Application filed December 30, 1915. Serial No. 69,349.

To all whom it may concern:

Be it known that I, KENNETH CLAIRE SMITH, a citizen of the United States, residing at Beaver Dam, county of Dodge, and 5 State of Wisconsin, have invented new and useful Improvements in Imitation Stoves, of which the following is a specification.

My invention relates to improvements in imitation stoves.

10 The object of my invention is to provide an advertising carton, composed of paste board or other suitable material, which may be distributed flat and later folded to a conformity with the general contour of a range 15 or stove, including base, warming closet, pouch feed and reservoir (the several members having those surfaces which are exterior in the assembled carton, printed to represent the various details of a stove's appearance) without cutting, gluing or other 20 manipulation aside from folding with the hands and which when so folded forms a coin tight receptacle which cannot be opened without destroying it.

25 In the drawings—

Figure 1 is a front elevation of my improved imitation stove.

Fig. 2 is a side elevation of the same.

Fig. 3 is a plan view.

30 Fig. 4 is a plan view of the blank from which the imitation stove is formed.

Fig. 5 is a side view of the same as it is prepared for shipment.

35 Fig. 6 is a side elevation, partly in vertical section, showing the various members of the stove partially assembled and with some of the flaps reversely bent to expose their inner faces.

40 Like parts are identified by the same reference characters throughout the several views.

In the construction of my imitation stove, I first prepare a blank having a lineal series of flexibly connected members 1, 2, 3, 4, 45 5, 6, 7, 8, 9, and 10 respectively. I preferably form the structure from cardboard and therefore the several members may be conveniently formed integrally with crease lines *a* at the meeting margins of the members, 50 to facilitate assembling the members in proper position. The member 2 is provided with lateral extensions from both side margins thereof. One of these extensions comprises a laterally extending lineal series of

members 12, 13 and 14. The member 12 is 55 integrally connected with the member 2, but a slot or slit *b* partially severs the same therefrom. The lateral extension of the other side margin of the member 2 comprises a set of members 15 and 16. The member 15 60 is also integrally connected with the member 2 and partially severed therefrom by a slit or slot *b'*.

The member 3 has a lateral extension 20, which is preferably connected integrally 65 with its side margin and is also in flexible joint connection with the end margin of the member 12 at *a'*. The member 4 is provided with lateral extensions 22 and 23 from its margins in flexible joint connection there- 70 with at *a''*. These members 22 and 23 are provided with flexibly jointed wings 25 ex- tending parallel with the main strip or series of strips 1 to 10 inclusive.

The member 5 is provided with laterally 75 extending members 27 and 28 which project on opposite sides of the member 5 from its outer end portion.

The various members above described are also provided with suitable interlocking ears 80 or connecting clips 30, 31, 32, 33, 34, and 35, the purpose of which will be hereinafter more fully explained. The surface of the member 1 is preferably formed or figured to represent the high closet back, together with 85 a smoke pipe *d* and damper *d'*. The surface of the member 2 is formed or figured to represent the top of a stove, including a set of griddles *e*. The surface of the member 3 is formed or figured to represent the front of 90 a stove, including a door *f* for the main oven, a door *f'* for the lower warming closet, and other doors *f''* and *f'''* etc. for access to fuel feed and ash pit chambers. The member 8 has its surface contoured or figured to 95 represent the front of a raised warming oven to be supported above the raised back plate formed by the member 1 when the parts are assembled.

The blank illustrated in Fig. 4 is folded 100 along the line *a'* to bring the members 1, 2 and 3 against the opposite side of the members 4 and 5 from that shown in Fig. 4, the member 1 lapping upon the member 5 between the members 27 and 28. The members 105 1 and 5 are then gummed together, as shown at *h* in Fig. 5, and in the zone indicated by dotted lines in Fig. 4. When the parts are

thus assembled as shown in Fig. 5, they may be packaged and shipped to destination.

The carton may then be folded into its resemblance to a stove by first folding members 6, 7, 8, 9 and 10 upon the reverse side of member 5 from that shown in Fig. 4. The member 6 will be retained in a flat position against the member 5, the members 7 and 9 will be swung outwardly to a horizontal position with the member 8 occupying a vertical position offset by the members 7 and 9 from the member 5. The member 10 will be tucked in between the member 5 and that portion of the member 1 above the space 10 where it is gummed to the member 5. This forms a rectangular receptacle representing a warming oven, supported above the top, 2 of the stove by the members 5 and 1. The ends of the rectangular chamber or warming closet may be closed by the wings 35, covered in turn by the members 27 and 28 respectively. The wings or flaps 34 may be pushed inwardly between the member 8 and the edges of the wings 35, thereby locking 20 the members 27 and 28 in positions at right angles to the back member 5.

Then by pulling outwardly upon the member 3, members 2 and 4 may be swung on their respective connections with the members 1 and 5, respectively, to horizontal positions as shown in Fig. 6. As the range top member 2 rises to a horizontal position the projections i on the members 27 and 28 will enter the slits b and b' which partially 30 sever the top member 2 from the members 12 and 15 respectively. The members 22 and 23 will then be folded inwardly. The wings 25 being passed into the rectangular space between the members 3 and 5 and the flaps 32 under the top member 2. As the members 22 and 23 reach nearly a vertical position the locking lips 33 are to be bent inward (but not creased) so that they may pass under the projections i of the members 35 40 27 and 28 and when they have completely passed said projections they will spring up behind such projections i thereby locking the coin receptacle or base of the range so that it cannot be opened without partially 50 or wholly destroying it.

Now the members 13 and 14 may be folded inwardly to form a rectangular cavity back of the member 20, the interlocking lip 30 is passed through a suitable slit 30^a cut 55 in the wing, 22, similarly the members 15 and 16 are folded to form the pouch feed, its top member 15 being a projection from the top member 2 and the member 16 assuming a diagonal or preferably a curved position and its locking lip 30 and engaging a slide 30^b in the member 23, said latter member now constituting the left side of the stove. The member 40 having a curved outer margin and which is flexibly connected with 60 the member 15 may be folded downwardly 65

to close the front end of the space underneath the top of the pouch feed member 15, and the locking member 31 may be tucked inwardly between the edge of this member and the member 16 would occupy the diagonal or curved position and support the pouch feed top member 15 as above described. 70

The member 23 is provided with a slot 42 which occupies a horizontal position when 75 the parts are assembled in the form of a complete range. Two vertical slots 43 and 44 are located at the respective ends of the horizontal slot 42. This forms an opening 80 that facilitates the use of the imitation stove as a coin receptacle, the coins being pushed through the slot 42. The vertical slots permit the walls of slot 42 to yield and permit the passage of the coin. 85

I claim—

1. An imitation stove comprising a strip of material having one face formed to represent in a lineal series of flexibly joined members, the back, bottom, front and top of a stove, laterally extending members flexibly connected with the bottom member of the stove and adapted to fold upwardly therefrom to form the sides thereof, and a set of interlocking flaps adapted to hold the members together when assembled to the form 90 of a stove. 95

2. An imitation stove comprising a strip of material having one face formed to represent in a lineal series of flexibly joined members, the back, bottom, front and top of a stove, in combination with end members of said lineal series adapted to form a raised warming oven supported from the back of the stove above the top thereof, laterally extending members flexibly connected with the bottom member and adapted to fold upwardly to form the sides of the stove and other laterally extending members connected with the raised portion of the back member and adapted to be folded at right angles to the back member and close the ends of the warming oven, the top of the stove being also provided with slits adapted to engage the lower margins of said last mentioned laterally extending members when the latter are bent or folded at right angles to the back. 110 115

3. An imitation stove formed integrally from a single piece of cardboard, sub-divided by crease lines into a lineal series of members forming the upper warming oven, the back, bottom, front, and top of a stove, and laterally extending flaps connected with the bottom member and adapted, when folded upwardly, to form the side walls 120 thereof, said members being figured to represent the respective walls of the stove, and means for locking the members in assembled position. 125

4. An imitation stove formed integrally 130

- from a single piece of cardboard, sub-divided by crease lines into a lineal series of members forming the upper warming oven, the back, bottom, front, and top of a stove, and laterally extending flaps adapted, when folded, to connect the top and bottom members, all of said members being figured to represent the respective walls of the stove, and means for locking the members in assembled position, said locking means comprising interlocking flaps engaging between the edges of the wall members. 40
5. An imitation stove formed from a single blank or piece of cardboard, suitably cut, creased and bent to constitute back, bottom, front, top and side members of a stove, together with a warming oven, reservoir and pouch feed attached thereto and similarly formed of cardboard members integrally connected with the others. 45
6. An imitation stove comprising the combination of a lineal series of integrally connected, flexibly joined cardboard members, composing the back, bottom, front and top 50 of the stove, said back member being extended above the top and said top member also having an extension gummed to the upwardly projecting portion of the back member and figured to represent a stove pipe. 55
7. An imitation stove comprising the combination of a lineal series of integrally connected flexibly joined cardboard members, composing the back, bottom, front and top of the stove, said back member being extended above the top and said top member also
- having an extension gummed to the upwardly projecting portion of the back member and figured to represent a stove pipe, together with an auxiliary set of members connected with the back member and adapted, when folded, to form a warming oven, the terminal member of said auxiliary set being engaged between the upper margin of the gummed top extension and said back member, substantially as described. 45
8. An imitation stove formed integrally from a single piece of cardboard, subdivided by crease lines into members forming the upper warming oven, the back, bottom, front, and top walls of a stove, and provided with a coin receiving slot, laterally extending flaps adapted, when folded, to connect the top and bottom members, and means for locking all the members in assembled position, said locking means being adapted to prevent access to the coins without destroying the stove. 50
9. A structural blank composed of an elongated strip provided with two sets of laterally extending flaps, said strip and the flaps having crease lines and formed to be folded on said crease lines to construct two spaced connected receptacles. 55

In testimony whereof I affix my signature in the presence of two witnesses.

KENNETH CLAIRE SMITH.
